R. J. STANLEY,
WINDOW SCREEN,
APPLICATION FILED OCT. 24, 1914.

1,140,413.

Patented May 25, 1915.

UNITED STATES PATENT OFFICE.

RAY J. STANLEY, OF CAZENOVIA, NEW YORK.

WINDOW-SCREEN.

1,140,413.

Specification of Letters Patent. Patented May 25, 1915.

Application filed October 24, 1914. Serial No. 868,396.

To all whom it may concern:

Be it known that I, RAY JAMES STANLEY, a citizen of the United States, and resident of Cazenovia, in the county of Madison, in the State of New York, have invented new and useful Improvements in Window-Screens, of which the following, taken in connection with the accompanying drawings, is a full, clear, and exact description.

This invention relates to certain improvements in window screens, preferably of the adjustable type, having a relatively wide range of adjustment to fit windows of different widths between the sash and top or bottom of the frame for ventilating purposes, and also to exclude insects, dust and other floating matter.

The main object is to provide a screen roll mounted in one end of the frame, and capable of being extended across frames of different lengths, and attached to the opposite end thereof in such manner that it may be easily and quickly released, and rewound upon the roller when desired, thus permitting the same screen to be used with rigid or adjustable frames.

Another object is to provide the adjacent edges of the lower and upper rails of the frame with lengthwise channels for receiving and guiding the adjacent edges of the screen, and holding said screen in a flat plane.

A further object is to provide adjustable connections between the frame sections for holding said sections in any position of adjustment to closely fit between the sides of the window frame, and at the same time, permitting the sections to be retracted when removing or replacing the frame.

A still further object is to construct the adjustable connections in such manner that they may be used as a means for positively retracting and extending the frame sections.

Other objects and uses relating to specific parts of the screen and its supporting frame will be brought out in the following description.

In the drawings Figure 1 is a perspective view of a window screen, embodying the various features of my invention, a portion of the upper rail of one of the sections being broken away to show the terminal end of the corresponding rail of the other section. Fig. 2 is an enlarged face view partly in section of the same screen. Fig. 3 is an en-

larged transverse vertical sectional view taken on line 3—3, Fig. 2. Figs. 4 and 5 are enlarged horizontal sectional views through the roller end of the screen frame taken, respectively, on lines 4—4 and 5—5, 60 Fig. 1. Fig. 6 is an enlarged detail sectional view through one end of the frame taken on line 6—6, Fig. 2, showing more particularly the manner of fastening the screen at this end, and also the connection 65 between the operating rod and frame section. Fig. 7 is an enlarged detail sectional view through a portion of one of the lengthwise rails, showing more particularly the manner of fastening the cross bar thereto. 70 Fig. 8 is an enlarged detail sectional view of the screen attaching means taken on line 8—8, Fig. 2.

This screen is used primarily for ventilating purposes, and consists of a rectangular frame composed of U-shape sections —1— and —2—, having respectively, upright parallel end bars —3— and —4—, the frame section —1— being provided with lower and upper parallel rails —5— rigidly secured at 75 one end to the upright bar —3—, while the section —2— is provided with lower and upper parallel rails —6— rigidly secured at one end to the upright bar —4—.

The rails —5— and —6— are spaced substantially uniform distances apart and are slidably interlocked with each other to permit the frame sections to be extended or retracted to fit between the upright casings of windows of different widths between the 80 sash and lower or upper portion of the window frame, as may be desired. These rail sections —5— and —6— are preferably made of sheet metal, tubular in form, so as to fit one within the other, except that their 85 inner lengthwise edges are provided with substantially flat flanges —7— which are spaced a slight distance apart to form relatively narrow vertical channels —8— for receiving and guiding the opposite lengthwise 90 edges of a screen fabric —9—, as the latter is drawn across the frame in a manner hereinafter described.

The main bodies of the rails —5— and —6— are substantially rectangular in cross 105 section, so that their lower and upper edges are substantially flat for close engagement with the adjacent portions of the sash or window frame, between which the frames are held, while the flange portions —7— are 110

brought closer together at or near the longitudinal centers of the main bodies to form the central lengthwise channels —8—, and at the same time, materially stiffening the rails, it being understood that the shoulders, as —10— formed by drawing the flange portions —7— closer together, serve to lock the telescoping portions of the rails against relative lateral or vertical movement, or rather to hold them in alinement, thereby maintaining all portions of the frame in a substantially flat vertical plane.

The screen —9— is preferably made of light cotton cloth or equivalent material, of such dimensions as to cover the entire opening in the frame when the latter is extended to the limit of its adjustment with its longitudinal edges entering the channels —8— and one end attached to a roller —11—, the opposite end being secured to a light but comparatively stiff reinforcing bar —12—, which, together with the roller —11—, serves to hold the fabric in a substantially flat plane against buckling, wrinkling or folding, the bar —12— being of approximately the same length as the vertical width of the fabric and is sufficiently thin to ride in the channels —8— as the screen is extended for use, said bar being provided with slotted ears —13— for detachable interlocking engagement with hooks —14— on the adjacent end bar —4—.

The roller —11— is journaled or stepped at its lower end in a bracket —14'— forming a part of the outer end of the lower rail —5—, the upper end of said roller being chambered at —15— for receiving a coil spring —16— and the inner end of a rod or stem —17— to which one end of the coil spring —16— is secured, the opposite end of said spring being attached to the roller —11—.

The outer end of the rod or stem —17— is preferably angular in cross section, as shown more clearly in Fig. 4, and is engaged in an open-sided slot —18— of a bracket —19— on the corresponding end of the upper rail —5— so as to hold the stem against turning, the slot being preferably open at the top to allow the rod or stem —17— to be readily inserted therein or removed when desired, and is provided near its lower end with a lateral enlargement forming a shoulder —20— with which the angular portion of the rod or stem is normally interlocked to prevent accidental displacement thereof, particularly when the screen is retracted upon the roller.

The intermediate portions of the lower and upper rails, and particularly the inner ends of the rails —5— of the section —1—, are connected by cross bars —21— having their ends rigidly secured to the adjacent portions of the rails by any suitable fastening means, as tongues —22—, which are

struck up from the opposite walls of the channels —8— and are forced into recesses —23— in opposite edges of the cross bar to firmly lock the latter against outward or lateral movement relatively to the frame section —1—. One of these cross bars also constitutes a convenient support for the operating means by which the frame sections may be extended or retracted, said operating means comprising in this instance a crank arm —24— pivoted at one end at —25— to one of the cross bars —21— and its other end provided with a handle —26— by which it may be rotated about the pivot —25—.

A clamping block —27— is pivotally connected to the crank arm —24— and provided with a lengthwise opening for receiving a rod or bar —28— which is pivotally connected at —29— to the end bar —4—, as shown more clearly in Figs. 1 and 2. This connecting rod or bar —28— is adjustable endwise in the apertured clamping block —27—, the latter being provided with a set screw —30— by which the rod may be firmly clamped to the block —27— to hold the frame sections —3— and —4— in their relatively adjusted positions.

The crank-arm —24— and connecting rod —28— constitute what may be termed a toggle connection between the frame sections —1— and —2—, and also constitute a toggle lock for holding said sections in their extended positions, by reason of the fact that the pivotal connection between the crank-arm —24— and clamping member —27— assume a position in a substantially straight line between the pivots —25— and —29— with the free end of the rod —28— resting on the hub of the crank-arm —24— as shown in Figs. 1 and 2. When it is desired to contract the frame lengthwise, it is simply necessary to swing the crank-arm —24— upwardly to the position indicated by dotted lines in Fig. 2, thereby reducing the length of the frame as an entirety and permitting it to be withdrawn from the window, or in a reverse manner replaced in the window.

The lower and upper brackets —14'— and —19— at opposite ends of the roller —11— are connected by a cylindrical section —31— forming with said brackets and the end bar —3— of the frame a suitable housing for inclosing and concealing the roller —11— and screen wound thereon.

The operation of my invention will now be readily understood with reference to the foregoing description, taken in connection with the drawings, and it is evident that all elements thereof may be substituted by equivalents without departing from the spirit of this invention. Therefore, I do not limit myself to the precise structure shown and described.

What I claim is:

1. A window screen, comprising two frame sections, slideable one upon the other, an upright roller housing on one end of one section, a roller in said housing, and a screen having one end attached to the roller to wind thereon, and its other end movable across the frame and provided with means for attaching it to the opposite side of said frame, spring means for automatically retracting the roller to tension the screen in any relative position of the frame sections.

2. A window screen, comprising a frame, having lengthwise channels in adjacent edges of opposite sides thereof, a roller housing on one end of the frame, an upright roller journaled in said housing, a screen attached at one end to the roller, and movable across the frame and having its opposite edges guided in said channels, the opposite end of the screen being provided with means for attaching it to the corresponding end of the frame.

3. A window screen, comprising two frame sections slideable one upon the other, a cross bar connecting opposite sides of one of the sections, adjustable connections between said cross bar and the end of the other section, and a screen stretched across the openings in both frame sections.

4. A window screen, comprising two frame sections slideable endwise one upon the other, a roller housing on one end of one of the sections, a roller journaled in said housing, a screen attached at one end to the roller, and having its other end provided

with means for attaching it to the opposite end of the frame, retracting means for the roller to automatically wind the screen thereon, and adjustable connections between the frame sections for holding the latter in their extended position against the action of the roller-retracting means.

5. A window screen, comprising a frame composed of sections adjustable endwise one upon the other, a screen covering the opening in the frame, a cross bar on one of the frame sections, a crank-arm journaled on the cross bar, and connections between said crank-arm and the other frame section for moving the last named section as the crank-arm is rotated.

6. A window screen comprising two frame sections slideable endwise one upon the other, and means for extending and retracting said sections, said means being adjustable to vary the degree of extension.

7. A window screen comprising frame sections adjustable endwise one upon the other, a crank-arm journaled on one of the sections, a rod pivoted to the other section, sliding connections between the crank-arm and rod, and means for clamping the sliding connections against relative sliding movement.

In witness whereof I have hereunto set my hand this 15 day of October 1914.

R. J. STANLEY.
